UNITED STATES PATENT OFFICE

2,325,900

AIRPLANE CONSTRUCTION

Joseph K. Anderson, Painesville, Ohio

Application January 2, 1942, Serial No. 425,476

2 Claims. (Cl. 244—117)

The present invention relates to new and useful improvements in the construction of airplane wings, fuselages, and other parts of an airplane, and has for its primary object to provide a frame construction for carrying the fabric or covering of the wings, fuselage, and other parts of the airplane.

A further object is to provide a frame construction which is strong and durable, relatively inexpensive to manufacture, in which the weight of the frame is materially reduced and which at the same time is otherwise well adapted for the purposes for which the same is intended.

Other objects and advantages reside in the details of construction as more fully hereinafter described and claimed, reference being had to the accompanying drawings forming part hereof, wherein like numerals refer to like parts throughout, and in which:

Figure 1 is a fragmentary perspective view of a portion of the frame showing the tube for receiving the fabric covering secured to one of the frame members.

Figure 2 is an end elevational view of the frame member.

Figure 3 is a fragmentary side elevational view of the frame member.

Figure 4 is a fragmentary side elevational view of a frame member showing the fabric covering in position in the fabric-retaining tube.

Figure 5 is a fragmentary longitudinal sectional view through one of the fabric-retaining tubes and showing the flexible strand for securing the fabric in the tube.

Figure 6 is a top plan view of a frame member for an airplane wing.

Figure 7 is a transverse sectional view thereof.

Figure 8 is a transverse sectional view illustrating the use of the frame construction for a tubular part of an airplane body, such as the fuselage.

Figure 9 is a side elevational view of a modified form of frame construction, with parts broken away.

Figure 10 is a fragmentary edge elevational view thereof.

Figure 11 is a similar view showing the opposite edge of the frame.

Figure 12 is an end elevational view showing parts of the fabric retaining tubes, and

Figure 13 is a similar view of the curved frame construction.

Referring now to the drawings in detail and with particular reference to Figures 1 to 7, inclusive, the numeral 5 designates a frame member generally which is composed of a pair of metal

tubes 6—6, each of the tubes being split longitudinally as shown at 7—7 for receiving the edge portion of a metal web member 8, the edges of the web being inserted through the slots 7 of the respective tubes and welded to the interior of the tubes at a surface thereof diametrically opposite from the slot 7. Openings 9 are formed in the web 8 to reduce the weight thereof.

When constructing an airplane wing, such as shown in Figures 6 and 7, plurality of fabric-retaining tubes 10 are welded, as at 11, to the top and bottom of the tubes 6, the tubes 10 extending at right angles to the tubes 6 and transversely of the wings. The tubes 10 at the top and bottom of the wing are preferably connected at the leading trailing edges of the wing. The outer surfaces of the tubes 10 are formed with longitudinally extending slots 12 and are adapted to receive the fabric covering 13 therein.

The fabric is retained in the tubes 10 in a conventional manner through the use of a flexible strand 14 inserted through an open end of the tubes 10 and through the loop 15 formed by the portion of the fabric disposed in the tubes 10. A handle 16 may be detachably secured to the strand 14 adjacent its inserted end for guiding the strand through the tubes, the handle 16 being movable along the slots 12.

The longitudinal frame members of the wing are designated at 17 and are constructed of the tubes 6 and web 8 and the fabric-covering receiving tubes 18 extend transversely thereof and are provided with the longitudinal slots 19 therein for receiving the fabric covering as heretofore explained.

In constructing a fuselage or other tubular body part of the airplane, such as indicated by the sectional view shown in Figure 8, the frame is designated generally at 20 composed of the ring-like tubular member 21 having the slot in its outer periphery for receiving the inner edge of a flat ring-like web 22 and secured therein in a manner as heretofore explained.

A plurality of openings 23 are formed in the web adjacent the outer edge thereof, the openings being interrupted to provide communication through said edge. Positioned in the openings are longitudinally extending tubes 24 corresponding to the tubes 10 and having slots therein registering with the interrupted edge of the openings 23 for receiving the fabric 25 secured in the tubes by its flexible strand 26.

Figures 9 to 12, inclusive, represent a modified form of flat frame construction in which the web 27 is provided at one edge with openings 28 for

receiving the fabric retaining tubes 29 and the other edge of the web is inserted into the continuous slot 30 of the tube 31 and suitably secured therein. The tube 31 at its side opposite from the slot 30 is formed with longitudinally spaced slots 32 through which project extensions 33 on the inner end of the web. The extensions are also provided with the openings 34 adapted for receiving the fabric-retaining tubes 35 at the opposite edge of the frame. The tubes 29 and 35 are secured in the openings of the web by welding or in any other suitable manner.

In Figure 13 a curved frame construction is illustrated embodying the web 36, extension 37, frame tube 38, and fabric-retaining tubes 39 and 40 at the opposite edges of the web and assembled as explained with respect to Figures 9 to 12, inclusive.

It is believed the details of construction and manner of use of the device will be readily understood from the foregoing without further detailed explanation.

Having thus described the invention what I claim is:

1. A frame construction for an airplane com-

prising a ring-like tube having a circumferential slot in its outer periphery, a ring-like web having its inner edge inserted in said slot and abutting the inner wall of the tube at a point diametrically opposite to the slot, said web having openings adjacent its peripheral edge and having a narrow entrance slot communicating with each opening, and axially extending fabric retaining tubes positioned in said openings and having fabric receiving slots in registry with the entrance slots of the openings.

2. A frame construction for airplanes comprising a web member having openings adjacent one edge, a tube having a longitudinal slot there-in receiving the other edge of the web, said tube also having spaced slots in its side opposite from the first-named slot, extensions on said other edge of the web one of said extensions projecting through each of the last-named slots outwardly of the tube, said extension also having openings therein, and fabric-retaining tubes positioned in said openings for extending at right angles to the web.

JOSEPH K. ANDERSON.
